UNITED STATES PATENT OFFICE.

HERAULT A. TRESTER, OF MILWAUKEE, WISCONSIN, ASSIGNOR TO METAL FORMS CORPORATION, OF MILWAUKEE, WISCONSIN, A CORPORATION.

ROAD FORM.

Application filed January 7, 1920. Serial No. 349,930.

To all whom it may concern:

Be it known that I, HERAULT A. TRESTER, a citizen of the United States, residing at Milwaukee, in the county of Milwaukee and State of Wisconsin, have invented certain new and useful Improvements in Road Forms, of which the following is a specification.

The present invention consists of certain novel improvements in road forms and is designed particularly for use preferably in the construction of concrete roads, though it may be employed in conjunction with roads of other types.

15 The primary object of the invention has been to provide a concrete or composition road form.

A further object of the invention is the utilization of special means for reinforcing 20 the concrete road form and for uniting the same with the road in conjunction with the building of which it may be used.

Another object of the invention is the employment of special means for protecting 25 the top or upper edge of the concrete form whereby to prevent possibility of disintegration thereof, in the event the form is employed as a track or support for a machine utilized in the road building operation. In 30 this connection it may be stated that today it is quite common practice where metal road forms are employed in the construction of concrete roads, to utilize the forms as rails of a track on which a finishing or 35 tamping machine may be supported to move concurrently with the road building operation. The design of the invention is to permit of the same service being performed by the road form herein set forth.

40 Other objects of the invention have been the reinforcement of the road form devised by me to make provision for the use of the form as a rail or track element, and the provision of other specific features of construction 45 appertaining to the anchoring of the cap-plate to the form and the anchoring of the form relatively to the road-bed itself.

The term road as used herein contemplates the various kinds of highways, pavements, sidewalks, and roads at present being constructed largely throughout the country.

50 In obtaining an understanding of the invention, reference is to be had to the following description in conjunction with the annexed drawings in which:

Figure 1 is a perspective view of a road form embodying the invention, shown partially in section and illustrated in an operative position relative to a road or road-bed of which it will form a part. 60

Figure 2 is a somewhat smaller view showing the cap-plate construction.

Figure 3 is a view illustrating a modification of the construction of Figure 2.

Figure 4 is a fragmentary perspective 65 view showing a modified form of reinforcement.

Figures 5 and 6 are sectional views showing primarily the cap-plate constructions of Figures 2 and 3, respectively, the form body 70 being itself illustrated in dotted lines.

The practical employment of my composition or concrete road form does away with the necessity, of course, of utilizing the metal road forms at present commonly employed, together with the labor incident to the constant removal and resetting of these forms during the progressive construction 75 of the road.

While I preferably utilize concrete composed of commonly known aggregates in proportions found best for the purposes of my invention, I do not wish to be limited to such materials alone, as it is evident that other substances may be employed to construct 80 my forms. The principle of my invention involves, of course, the employment of a form which ultimately becomes a part of the road itself constituting an edge wall or section, vertically, one at each side of 85 the road, and firmly united with the road.

My form itself is of simple construction, being designated A in the drawings and comprising a molded section of concrete or suitable composition material, said section 90 preferably having a straight inner wall and an outer wall which inclines toward the inner wall in an upward direction.

Longitudinal reinforcing rods are imbedded in the form in its construction and 100 are equipped with lateral hook-like extensions which project laterally from the form as seen in Figure 1 so as to become imbedded in the road B when the latter is constructed, thus forming a uniting means between the 105 form A and road B.

Figure 2 shows a cap-plate C protecting the upper edge portion of the form A and equipped with downwardly struck out 110 tongues 3 to anchor the same in the body of

the form. The plate C will be applied to the form A in the molding operation.

Figure 3 illustrates a construction like Figure 2 excepting that the cap-plate C has 5 a skirt C' on its inner edge and forming a vertical reinforcing element lending rigidity to the form vertically thereof. Offstanding from the skirt C' are anchoring tongues 4 to become imbedded in the road B.

10 The cap-plate C is an effective means to prevent possible disintegration of the top of the form by lodgment of small stones or the like between the same and the wheels of a machine which may travel along the form.

15 In Figure 4 the form is strengthened vertically by a corrugated plate D equipped with the struck out lateral tongues 5 to become imbedded in the road B. This construction of form may or may not have a 20 cap-plate being illustrated without the same.

Under practical conditions of service, my forms A are laid in spaced relation upon the sub-grade on which the road is to be constructed. The reinforcing rods 1 will preferably project slightly at one end of each section of the form A to enter recesses in the corresponding adjacent end of a second section or form. In this manner the forms may be aligned as regards the various sections. Once the forms are in position the road may be constructed as usual and if it be of concrete as illustrated, the forms will be firmly united therewith when the road hardens. The foregoing, of course, involves a 35 new method of laying concrete roads.

Having thus described my invention, what I claim as new is:

1. A road form constructed of composition material, combined with a longitudinal reinforcing element therefor, and anchoring elements connected to the longitudinal element and projecting laterally from the form at a side thereof so as to extend a considerable distance from said side to become embedded in and anchor the form to an abutting road bed of subsequently constructed plastic material.

2. As a new article of manufacture, a composition road form, a cap plate at the 50 top of the form for reinforcing the said form and protecting the same when used as a rail, and means carried by the form for anchoring it to a road bed subsequently constructed at one side thereof.

55 3. As a new article of manufacture, a composition road form, a vertical reinforcing plate for the form, and anchoring elements connected to the plate and projecting laterally from the form for engagement with a road bed subsequently constructed at one side of the form.

4. As a new article of manufacture, a road form, of plastic composition, and a 65 cap-plate for reinforcing said form and enabling it to be used as a rail to support port-

able road building machinery in constructing an abutting road bed of plastic material.

5. As a new article of manufacture, a road form, of plastic composition, a cap-plate for said form, and means anchoring 70 the cap-plate to the form and for anchoring the form to a road-bed built at one side of the form.

6. As a new article of manufacture, a composition road form, a longitudinally 75 extending reinforcing plate for the form, and anchoring elements stamped from the plate and bent laterally therefrom for engagement with a road bed subsequently constructed at one side of the form.

7. As a new article of manufacture, a composition road form, a longitudinally extending reinforcing plate having an edge portion thereof bent laterally to provide a 85 cap for the upper edge of the form, and anchoring elements associated with the plate and projecting laterally from the form for engagement with a road bed subsequently constructed at one side of the form.

8. As a new article of manufacture, a composition road form, a reinforcing plate extending longitudinally of the form and having an edge portion thereof bent laterally to provide a cap for the top of the 90 form, anchoring members stamped from the said cap and embedded in the form, and a second set of anchoring members stamped from the plate and projecting laterally from the form for engagement with a subsequently constructed road bed.

9. As a new article of manufacture, an elongated road form adapted to be used in constructing road beds of plastic material, said form having a comparatively broad flat base and a narrower head portion the latter adapted to form a rail head to support the wheels of portable road building machinery, and also having a straight inner wall to engage the plastic concrete of a road at a side of the subgrade, the outer side of the form inclining downwardly and outwardly, and the said outer side, the head portion and inner wall forming a substantially continuous surface from the base at the outer side to the base at the inner side.

10. As a new article of manufacture, an elongated road form adapted to be used in constructing road beds of plastic material, said form having a comparatively broad flat base and a narrower head portion adapted to form a rail to support portable road building machinery, and also having a straight inner wall to engage the plastic concrete of a road at a side of the subgrade, the outer side of the form inclining downwardly and outwardly and the said outer side, the head portion and inner wall forming a substantially continuous surface from the base at the outer side to the base at the inner side, the said head portion comprising 110 115 120 125 130

ing a metallic member of substantially inverted U form extending upwards as a part of the outer side of the form, horizontally to provide the head portion and thence 5 downward as a part of the inner wall of the form.

11. As a new article of manufacture an elongated road form adapted to be used in constructing road beds of plastic material, 10 said form having a flat and comparatively

broad base and being tapered upwardly to a straight and narrow upper edge which is adapted to be used as a rail for supporting portable road building machinery, said upper edge being reinforced and one of the 15 faces of the form being adapted to engage and support the plastic material of the road bed.

In testimony whereof I affix my signature,
HERAULT A. TRESTER.
